PISTON EXPANDER

George C. Beck, Spokane, Wash.

Application December 22, 1937, Serial No. 181,057

2 Claims. (Cl. 309—12)

The object of this invention is to provide a novel expanding device for the split skirts of pistons.

It is a feature of this invention to provide an expander means that is self-sustaining in the performance of its function.

It is a further feature to provide an expander means that is secured to the skirt, either when initially manufactured or later as an accessory, and which is adapted to perform its expanding function without being detached from the skirt.

A further feature consists in a self-sustaining expander that performs its function by having its shape altered.

15 A further feature consists in an expander that is self-sustaining but which is also capable of yielding under the recoil of excessive expansion of the skirt.

The invention resides and is claimed in combination with a piston and also as an article of manufacture.

The invention has many other features and objects which will be more fully described in connection with the accompanying drawing and 25 which will be more particularly pointed out in and by the appended claims.

In the drawing:

Fig. 1 is a view in elevation of a piston having a split skirt and showing the device of my invention applied thereto in dotted lines.

Fig. 2 is a view of the piston looking from the left of Fig. 1.

Fig. 3 is a sectional view on line 3—3 of Fig. 1, with the expander in elevation and partly in section.

Fig. 4 is an inside view looking in the direction of the arrow in Fig. 3.

Fig. 5 is a view similar to Fig. 3, showing a modified form of expander.

40 Fig. 6 is a view in side elevation of the expander shown in Fig. 5, detached from the piston.

Fig. 7 is a perspective of the initial shape of the bar before the same has been bent to the desired form.

45 Like characters of reference designate similar parts throughout the different figures of the drawing.

I have shown the device of my invention applied to a type of piston in which the head is indicated at 1, and is provided with the usual complement of ring grooves 2. The piston is provided with a skirt 3 which is hung from the head 1 by an interior skeleton frame consisting of vertical members 4 and horizontal members 5. Bearings 6, for the crank pins, are shown formed

integral with the vertical frame members 4. From Figs. 1 and 2, it will be seen that there is a clearance between the bottom of head 1 and the top 7 of the skirt 3, and the latter is split or slit from the top 7 to the bottom 8, as indicated at 9.

It will be understood that my invention is not limited to this particular type of piston and is merely illustrated in connection therewith to show how it may be applied thereto.

It is further understood that my invention is not limited as being applied to a skirt slit located in the particular position shown as it is merely essential that the skirt be divided in some way or in some location in order that the skirt may be expanded, and further, the extent to which it is divided is not material so long as the slit is sufficient to permit of expansion of the skirt.

In the specific form shown, my improved expander is made from a bar of spring steel as 20 shown in Fig. 7, and as indicated at 10, and the same may, as shown, be flat so that it will occupy a single plane. It is first heated and shaped to a form, to be later described, while hot, and it is then allowed to cool slowly in the air, or at 25 any desired annealing low temperature so that it will not be tempered to the condition of resiliency that would be required from a spring having a substantial responsive flexure. In the latter event the heated and shaped bar would 30 of course be cooled in water or oil or by any sudden and well known means. Thus, after my expander has been shaped and given a sub-normal temper comparable to annealed steel, it will have a high degree of toughness and a low degree of 35 resiliency, and these are the qualities which make the finished resilient article what I hereinafter term, "self-sustaining" in any shape to which it may be altered, after being installed, and whereby under excessive piston recoil, it will be 40 capable of yielding and thereafter retaining the position or shape which such excessive recoil stress has imparted to it.

Reference will next be made to the preferred form of expander as shown in Figs. 3 and 4.

It will be seen that the bar 10 has been bent or shaped to form a centrally disposed arch 11 and that the ends 12 have been bent to abut against the inner face of the skirt, dependent upon the diameter thereof. Means is provided 50 for anchoring the expander bar in place and, as shown, such means take the form of rivets 13, the heads 14 being disposed inside the skirt and the remaining ends 15 being counter-sunk either flush with the periphery of the skirt or slightly

less than a flush relation therewith, which is a mechanical matter not important to the invention. In fact, these rivets form an anchorage means which permits the bar to take its thrusts in the direction of its length, and any means such as sockets, for instance, which would perform this function, would be within the scope of the invention.

It will now be clear that the expander bar 10 is disposed in substantially transverse relation to the length of the slit 9 and that the arch 11 bridges said slit, and that the arch is formed so that it will be in spaced relation from the slit portion of the skirt. In other words, the central portion 11 arches away from the feet or attaching terminals 12.

Next referring to the modified form shown in Figs. 5 and 6, it will be seen that the arched feature is retained and for much the same purpose as in the preferred form except that there is a series of arches, the bar 16, from its initial flat form, as in Fig. 7, being corrugated, as indicated at 17. However, this modified form is otherwise prepared in the same manner as the preferred form. The entire bar 16 is curved so that the radially outer corrugations or hills 18 abut against the inner face of the skirt while the radially inner hills 17 project inside the skirt or toward the longitudinal axis thereof. I have shown the feet or terminals 19 riveted to the skirt 20, the heads 21 being inside the latter, and the outer ends 22 of the rivets being counter-sunk. However, it is not absolutely essential that the hills 18 should abut the skirt in order that the expander may function efficiently. The slit is shown at 23.

While the operation and use of my invention may be clear from the foregoing, they will be briefly recapitulated as follows:

It may be stated that the most important function of this invention is to take up piston wear. When the car is new, or when new pistons are fitted to re-bored cylinders, the pistons fit so tight that my expander is not called upon to function. However, just as soon as wear forms an objectionable clearance, then a few taps in the arch 11, tending to flatten the same, or a like treatment of any of the arches 17, will serve to lengthen the expander bars and thereby spread or expand the piston skirts. The expanding stress on the skirts will not be the same as would be exerted by a wholly rigid expander that might have threaded adjustment, for instance, but on the contrary, the expansive stress is of a yielding nature, and this is a vastly important quality.

Suppose for instance, that the arches were flattened to a too great extent and that after the engine got heated, the piston expansion added to the spread by the expander, caused the pistons to "freeze" in the cylinders, then, and in that event, my improved expanders would yield before such "freezing" action could take place, by reason of the fact that my expanders have a minute capacity to yield under all conditions and are never wholly rigid.

It tapping either form of arch, the latter will of course be slightly deformed from its original shape in order to exercise an expanding thrust on the skirt, but of course such expansion will always be slight and hence the arch would never actually be entirely flattened against the wall of the skirt. Therefore it will be clear that even after maximum usage, and even after several successive expansions have been effected, there will always be an arched central position spanning or bridging the slit in the skirt.

This is a very important feature of the invention since the arched form not only insures an effective spreading action, but it additionally insures a possible yielding action which would not be true if the arch in the preferred form, or all the arches of the modified form, were ever wholly flattened out. It will be clear that my improved bar expander would be just as unyielding and rigid as a straight flat bar if it were ever completely flattened.

Therefore it will now be clear that by reason of the slow cooling of the shaped bar whereby it will have a low coefficient of resiliency, and the added fact that it always presents an arched form, I am able to achieve the dual function of a resilient or spring expander that is self-sustaining in any shape changing or deformed contour to which it may be subjected.

It will thus be seen that the central portion 11, or any one of the corrugations 17, may be flattened or altered in such a manner as to maintain tension of the bar in distending the piston skirt, in compensation for wear, or to increase the tension as the condition of the piston warrants.

It will be seen that my improved expansion bar 23 is located far enough below the horizontal skeleton frame members 5, and at a sufficient elevation above the bottom 8 of the skirt 3, to make expansion of the skirt effective.

I desire to point out some of the fundamental 30 distinctions between a leaf spring expander and my improved bar expander.

A leaf spring is always relatively thin and is tempered to a relatively high degree of resiliency and is accordingly brittle. Therefore, such a 35 spring will instantly recoil to its original form when any attempt is made to deform or alter its shape unless the spring is re-tempered.

On the contrary, my expander is in the form of a spring steel bar, which differs fundamentally 40 from a leaf spring, by reason of the fact that this bar is of sufficient thickness or cross section to be self stable or self sustaining, as a result of its inherent stability, and irrespective of the fact that it is tempered. This bar is further distinguished from a leaf spring expander by the 45 fact that it is tempered to a low degree of resiliency and has a high degree of toughness. Hence, my bar can be tapped by a hammer, or wedged by a tool, to alter its original form and the bar will not only retain its altered form, but also, whatever resiliency was originally imparted to it during the tempering process.

While in Figs. 3 and 5, I have shown the ends 12 of bar 11, and the ends 19 of bar 16, riveted to the skirt, as a means of anchoring the bars thereto, still, it will be understood that in the broadest concept of the invention, the end 12 and 19, respectively, are disposed in distending relation to the piston skirt since the function of these bars is always to distend and not to contract the skirt, and hence I do not wish to be limited to the particular means shown of connecting or operatively locating the bars.

It is believed that the invention will be fully 65 understood from the foregoing description and I do not wish to be limited thereto except for such limitations as the claims may import.

I claim:

1. As a piston expanding device for pistons having a split skirt, a substantially rigid bar permanently deformable under hammer blows and having a low factor of resilience comparable to annealed steel, said bar having its ends fixedly secured to the inner face of the piston skirt on 75

opposite sides of the slit therein, the bar between the ends being of sinuous formation with the curves of the sinuous portion extending alternately inwardly away from the skirt and outwardly toward the skirt.

2. As a piston expanding device for pistons having a split skirt, a bar formed of a single composition of metal having a single coefficient of contraction and expansion and the ends of said bar being fixedly secured to the inner face of the

piston skirt on opposite sides of the slit therein, said bar having at least one portion arched inwardly away from the skirt, and said bar being substantially rigid and having such a low factor of resilience comparable to annealed steel that when said arch is flattened under hammer blows to expand the piston said bar will retain its deformed shape without requiring removal from the piston. 5
